M. MEYERSON,
FOLDING CARRIER,
APPLICATION FILED JAN. 10, 1918.

1,323,715.

Patented Dec. 2, 1919.

UNITED STATES PATENT OFFICE.

MAX MEYERSON, OF NEW YORK, N. Y.

FOLDING CARRIER.

1,323,715.

Specification of Letters Patent.

Patented Dec. 2, 1919.

Application filed January 10, 1918. Serial No. 211,132.

To all whom it may concern:

Be it known that I, MAX MEYERSON, residing at New York, in the county of New York and State of New York, have invented 5 certain new and useful Improvements in Folding Carriers, of which the following is a specification.

This invention relates to a folding carrier and the object of the invention is to provide 10 a carrier which may be made up of fiber or card board and which is reinforced to sustain heavy strains.

A further object is to provide a carrier which is particularly adapted for the carrying 15 of such articles as camp or funeral chairs and the like and which is adapted to be folded into a compact strong and attractive parcel when not in use.

Other objects and aims of the invention 20 more or less specific than those referred to above, will be in part obvious and in part pointed out in the course of the following description of the elements, combinations, arrangements of parts and applications of 25 principles, constituting the invention; and the scope of protection contemplated will be indicated in the appended claims.

In the accompanying drawings which are to be taken as a part of this specification, 30 and in which I have shown merely a preferred form of embodiment of the invention:

Figure 1 is a perspective view of a carrier constructed in accordance with this invention, the same being shown collapsed.

Fig. 2 is a transverse sectional view taken substantially upon the plane of line I I of Fig. 1.

Fig. 3 is a similar view to that shown in 40 Fig. 2 but showing the carrier partly open.

Fig. 4 is a diagrammatic view corresponding to the showing in Fig. 3 but the carrier being fully extended.

Fig. 5 is a diagrammatic view in top plan 45 showing the carrier in dotted lines partly extended and in full lines fully extended.

Fig. 6 is a sectional view corresponding to portions of Fig. 4 but the parts being enlarged to disclose the details of construction, 50 and

Fig. 7 is a similarly enlarged fragmentary sectional view of the hinge employed for connecting certain of the parts together.

Referring to the drawings for describing 55 in detail the structure which is illustrated therein the reference character L indicates

the base portion, the reference character G indicates the body portion, and the reference character H indicates the cover portion.

The base portion L is of tray shape and 60 includes a bottom wall 1 having up-turned marginal flanges 2. At certain points the flanges 2 are reinforced by metallic angle pieces 3 preferably arranged on the outside surface and rigidly fixed in position by suitable rivets or the like 4. These are disposed for receiving wear when the parcel is being moved about and also for retaining the flanges in a proper right angular relation to the bottom wall. Corner irons as 5 are 65 also provided for reinforcing the corners.

The cover part H is identical in shape and construction to the base part except that it is slightly larger so as to be able to telescope over the base portion when the carrier 70 is collapsed as clearly seen by reference to Figs. 1 and 2.

The body part G is made up of a rear wall 6, a front wall 7, and opposite end walls 8. The end walls 8 are each made up 80 of two sections as 9 and 10 hinged together at a central point as 11. The sections 9 are hinged to the rear wall 6 as at 12 and the sections 10 are hinged to the front wall 7 as at 13. By this arrangement the front 85 wall 7 may be moved toward or away from the rear wall 6 by the simple expedient of bowing inwardly the sections of the end walls 8, as clearly shown by the dotted lines in Fig. 5. The rear wall 6 is hinged at its 90 lower edge to the adjacent flange 2 of the base portion L as at 14 so that it may swing from the position shown in Fig. 3 downwardly into the base portion as shown in Fig. 2. The front wall 7 is provided with 95 one or more eyelets or openings 15 adapted to receive one or more retaining members 16 which are carried by the front flange 2 of the base portion.

The retaining members 16 may be of any 100 desired construction and are adapted to extend through the openings 15 and to provide easily releasable inter-engagement with the front wall 7 such that said wall 7 may be moved into and out of its fully extended position at will and such that when said wall is in its fully extended position it will be suitably retained against displacement except upon the intentional release of the retaining member 16.

The edge portions of any or all of the walls described may be reinforced by me-

talic U-shaped binding strips as 17 if desired. In fact these binding strips may be employed as reinforcing elements for receiving rivet connection, as for instance where 5 the rivets as 18 retain the hinges 14 fixed to the rear wall 6.

The hinges 14 also may be provided with angularly disposed portions 19 which extend along the inner surface of the bottom wall 1, 10 for reinforcing purposes, if desired.

In order to strongly reinforce the wall members of the body portion G against possible collapse in a vertical direction, said walls may be provided with vertically disposed 15 reinforcing strips as 20. These strips may be arranged at any suitable points but preferably are arranged so that their opposite ends coincide with the position of the angle braces 3 of the base and top portions, 20 thus to transmit vertical strains directly to these reinforcing and wear resisting elements.

The axis of the hinges 14 is arranged in a plane somewhat above the upper surface of 25 the bottom wall 1 of the base portion so as to afford ample space for the parts of the body portion when the body portion is thrown down. The reinforcing strips 20, however, are of a length so that when the 30 body portion is in vertical position said strips extend below the body portion into engagement with the bottom wall 1, as most clearly seen in Fig. 6. Preferably they are mounted to slide upwardly when required to 35 accommodate the downward swinging of the body member.

If desired of course the reinforcing strips 20 may be positioned exteriorly of the walls of the body member.

40 The hinge 14 is preferably of metal and may be continuous throughout the length of the lower edge of the body member or it may be in sections as illustrated.

The type of hinge employed for connecting the wall members of the body portion together is clearly illustrated in Fig. 7, and comprises a strip 21 of flexible material such as canvas or the like held by its opposite longitudinal edges to the edges of adjacent 50 portions of the walls hinged. Strips as 22 of card board or the like extend along the opposite edges of the member 21 and serve to receive rivets 23 which extend through the wall members, through the member 21, and through said strips. In this way a continuous strong and substantial hinge is provided. The hinges 11, 12 and 13 are preferably constructed in this manner.

60 All of the wall members described are preferably formed of thin sheet card board or fiber board which may be varnished or otherwise finished at one or both of its surfaces so as to produce an attractive appearance. The reinforcing elements above described are so arranged as to maintain the

shape of this material and so as to prevent collapse or buckling of any of the parts under such stresses or strains as may be applied in ordinary use.

As many changes could be made in this 70 construction without departing from the scope of the invention as defined in the following claims, it is intended that all matter contained in the above description or shown in the accompanying drawings, shall be interpreted as illustrative only and not in a limiting sense.

Having thus described my invention, what I claim as new and desire to secure by Letters Patent is:—

1. A folding carrier comprising a base portion in the form of a tray, a body portion pivotally connected to swing into and out of said tray, the body portion including collapsible parts, a hinge providing the 85 pivotal connection between the body portion and said tray, said hinge being arranged to define a space within the tray for accommodating the collapsible parts of the body portion when said collapsible parts are collapsed, and to support the body part away 90 from the bottom wall of the tray when said collapsible parts are not collapsed.

2. A folding carrier comprising a base portion in the form of a tray, a body portion 95 pivotally connected thereto, the body portion including collapsible parts, a hinge providing the pivotal connection between the body portion and the tray, said hinge being arranged to support the body portion away 100 from the bottom wall of the tray when said collapsible parts are not collapsed, and retaining means co-operative between the tray and the body portion of a character to retain the body portion in non-collapsed position and also to serve as an auxiliary to the hinge in supporting the body portion away from the bottom wall of the tray.

3. A folding carrier comprising a base portion, and a body portion, the body portion including collapsible parts, a hinge pivotally connecting the body portion with the base portion, said hinge being connected at one side only of the body portion so that said body portion may swing as an 115 entity upon said hinge, and said hinge serving directly to support said side of the body portion away from the bottom wall of the base portion when said collapsible parts are not collapsed, and other means for supporting the opposite side of the body portion away from said bottom wall of the base portion when said body portion is not collapsed.

4. A folding carrier comprising a base portion and a body portion, the body portion 125 comprising collapsible parts, means for connecting the body portion to the base portion operable when the body portion is not collapsed to support the body portion above the bottom wall of the base portion, a cover 130

portion, and reinforcing strips for the body portion extending throughout the height of the body portion into engagement with both said cover portion and the bottom wall of 5 said base portion when the body portion is not collapsed.

5. A folding carrier comprising a base portion in the form of a tray, a body portion comprising collapsible parts, a plurality of angle brackets fixed to the tray disposed for reinforcing the side walls thereof, 10 a cover portion, a plurality of reinforcing members carried by the cover portion and

a plurality of reinforcing members carried by the body portion extending throughout 15 the height of the body portion and having their opposite ends disposed in coöperative relation with the angle brackets of the base portion and the reinforcing members of the cover portion.

In testimony whereof I affix my signature in the presence of two witnesses.

MAX MEYERSON.
